SOOT CLEANER

Frederick W. Linaker, Forest Hills, N. Y.

Application January 17, 1940, Serial No. 314,237

27 Claims. (Cl. 122—392)

This invention relates to soot blowers of the retractable type, and to elements thereof, and provides improvements therein.

Soot blowers are used for removing soot slag formation or the like from the tubes of steam generating boilers, economizers and the like, which soot or other solid products of combustion, is carried by the gases resulting from the combustion of fuel and settles out from said gases on the tubes and other parts of the furnace on their way to the stack and impair the efficiency of the heater or boiler.

The temperature within the boiler or furnace is often high and as the blowing of the soot is done periodically, it is advantageous to retract the parts of the soot blower which are inserted into the boiler or furnace to protect them, in the intervals between the cleaning periods.

The present invention provides improvements in the retractable type of soot cleaner. It provides for precise positioning of the cleaner element in its inserted position, or positions, so that a maximum or approximately maximum performance of the apparatus may be obtained. It provides a control for the cleaner element by which an initial and predetermined angular position of the nozzles of the cleaner element is maintained during insertion and retraction and a regular arc of movement of the nozzles obtained so that the jets from the nozzles, during the rotation of the cleaner element start from and stop at positions which are predetermined so as to always sweep the desired parts on the inside of the boiler or furnace. The invention further provides for the opening and cutting off of the steam supply to the cleaner element automatically through the instrumentality of the mechanism employed for inserting and retracting the cleaner element. It also provides a mechanism which is simple, reliable and easily operated by the attendant and which reduces the effort which the attendant has to exert in using the apparatus, particularly in retracting the cleaner element. The invention provides the foregoing advantages in a soot blower having a cleaner element which is inserted in one step and has one operating position as well as in a soot blower having a cleaner element which is inserted in a plurality of steps and has a plurality of operating positions.

The invention further provides an improved cleaner element provided with internal reinforcements which are cooled by the steam which flows to the nozzles, and which is thereby

enabled to resist deformation and retain its form in very hot locations within the furnace.

Two embodiments of the invention are illustrated in the accompanying drawings, wherein:

5 Figs. 1 to 8 inclusive illustrate one embodiment, in which the distance to which the cleaner element is inserted in the boiler or furnace is relatively short, for example, six feet or less, and Figs. 9 to 20 inclusive illustrate a second embodiment most appropriate where the distance to which the cleaner element is inserted within the boiler or furnace is long, as for example, over six feet, and with which the cleaning is done in steps with the cleaner element inserted at progressively greater distances within the boiler or furnace.

Fig. 1 is a view of the soot blower in side elevation, broken away through the middle portion to reduce the width of the drawing on the sheet.

20 Fig. 2 is a transverse sectional view on the line II—II, Fig. 1, looking toward the left.

Fig. 3 is a partly diagrammatic view showing a side elevation like that of Fig. 1 on a reduced scale, and illustrating the said blower mounted on the wall of the furnace with the cleaner element inserted and directing cleaning jets against water tubes within the boiler or furnace.

25 Fig. 4 is a view similar to Fig. 1, with parts in longitudinal section, and showing the parts in a position which they occupy when the cleaner element is inserted within the boiler or furnace; in Fig. 1 the parts are shown in position which they occupy when the cleaner element is retracted.

30 Fig. 5 is a longitudinal sectional view on an enlarged scale of the valve, through which steam is supplied to the cleaner element, and its operating mechanism, the valve being shown in its automatically opened position.

35 Fig. 6 is a transverse section on the line VI—VI Fig. 4 looking toward the left, and likewise on the line VI—VI Fig. 7.

Fig. 7 is a sectional view of the parts shown in Fig. 6, at right angles to the view shown in Fig. 6.

40 Fig. 8 is a view similar to Fig. 6, illustrating the parts in a different position.

45 Figs. 6, 7 and 8 illustrate certain parts of the mechanism related to the inserted position of the cleaner element and to the control of the arc of movement of the cleaner element through which it is turned in carrying out the blowing of the soot.

50 Fig. 9 is a view in side elevation of an embodiment in which the cleaner element is inserted

and operated stepwise into the boiler or furnace, with the parts shown in retracted position.

Fig. 10 is a view similar to Fig. 9 on a smaller scale, in which the means for arresting the cleaner element at a plurality of inserted positions is better shown.

Fig. 11 is a somewhat diagrammatic view, the parts of the soot blower being shown in top plan view, and the boiler being shown in horizontal section. The plurality of inserted positions is shown diagrammatically in this view.

Fig. 12 is a top plan view of the track on which the carriage which carries the cleaner element, runs.

Fig. 13 is a detail view, showing the carriage and some of its associated parts, partly in side elevation and partly in section.

Fig. 14 is a transverse sectional view on the line XIV—XIV, Fig. 9.

Fig. 15 is a detail view in side elevation of one of the stops and an associated part on the rotary head of the cleaner, by which the stepwise insertion of the cleaner element is controlled.

Fig. 16 is a detail view partly in side elevation and partly in section, of the valve for controlling the admission of steam to the cleaner element, and of certain associated parts through which the opening and closing of the valve is automatically controlled.

Figs. 17 and 18 are respectively, a longitudinal section and a cross-section through a cleaner tube, and illustrating an improved construction thereof, according to the present invention.

Fig. 19 is a cross-sectional view of a cleaner tube embodying the improvement of the present invention in another form of embodiment.

Fig. 20 illustrates a form of the soot blower in which the insertion and retraction is motor controlled.

Referring to the drawings, and particularly to Figs. 1 to 8 inclusive, numeral 10 designates the cleaner element, 12 the carriage and 14 a rotatable head mounted on the carriage, and attached to the outer or right-hand end of the cleaner element 10. The carriage 12 moves back and forth on a track 16 to insert the cleaner element into, and retract it from the space within the boiler or furnace containing the tubes or other parts to be cleaned by blowing the soot or other matter which has deposited thereon from the furnace gases. The cleaner element 10 is provided with one or more nozzles for directing jets of steam on to the parts to be cleaned, one nozzle 20 being here shown. One of the furnace walls has an opening 22 therethrough, through which the cleaner element 10 is inserted into the space within the boiler or furnace, and through which it is also retracted. As here shown, instead of withstanding the cleaner element entirely from the boiler, the end of the cleaner element with its nozzle 20 may, in its retracted position, rest within the recess in the furnace wall formed by the opening 22, as best shown in Fig. 3. The soot blower is attached to the boiler or furnace adjacent the opening 22. The attachment may be made by a suitable means, as screws which pass through a supporting or wall plate 24 into the side wall of the furnace, or into a sleeve-casting 25 built into the furnace wall, where it is best shown in Fig. 1. The opening 22 is ordinarily made of larger diameter than the cleaner element 10, and the opening may be closed around the cleaner element by suitable means, as an annulus 27. However, means, as hanger rods (not shown) attached to an overhead beam or the ceiling may

be provided for giving additional support to the soot blower.

Means for moving the carriage 12 to insert the cleaner element 10 into and retract it from the space within the boiler is included. This means comprises a pulley 30 over which passes an endless pull-chain or the like 32. The pulley 30 is attached to a shaft 35 mounted in brackets 36 attached to or forming part of the wall plate 24. The shaft 35 has fixed thereon a sprocket wheel 38 around which passes a sprocket chain 39. Near the outer end of the track 14 is mounted in a suitable manner, another sprocket wheel 40 around which the sprocket chain 39 also runs, so that the chain 39 has a flight parallel to the track 16. For constructional purposes the sprocket chain 39 and the sprocket wheels 38 and 40 are duplicated, as most clearly shown in Fig. 2. The carriage 12 is connected to the sprocket chain 39 through a pin or projection 42 on the sprocket chain and an arm 44 attached to the carriage having a slot 45 therein into or through which the pin 42 extends. The slot 45 provides a limited loss of motion between the chain and the carriage 12 for a purpose to be hereinafter described.

Means are provided for rotating the rotatable head 14 and the cleaner element 10 fixed thereto, by which the cleaner element 10, when inserted into the space within the boiler, may be turned so that the jets which issue from the nozzle on the cleaner element may be caused to appropriately play on the parts to be cleaned. This means may comprise a pulley 50 having thereon a suitable pull-chain or the like 51. The pulley 50 is fastened upon a shaft 53 held in suitable brackets 56 on the carriage 12. The shaft 53 has fixed thereon a pinion 57, which is advantageously a worm pinion which latter meshes with a gear 59 attached to the rotatable head 14.

Steam is supplied to the cleaner element 10 from a supply-pipe 60 through a valve 62 and a gooseneck 65 having an extension 66 which extends within the cleaner element 10 so as to telescope therewith, and remain lapped or telescoped with the element in its position of farthest insertion within the boiler. A steam-tight connection between the tube 66 and the rotatable head 14 is effected by means of a suitable gland or packing 68.

Means are also included for preventing rotation of the rotatable head 14 while the cleaner element 10 is being moved to and from its inserted cleaning position. This means advantageously comprises a flat 70 on one of the parts of the means for rotating the head 14, as a collar 72 keyed to the shaft 53, and a rail 75 extending along and parallel to the path of travel of the carriage 12. The rail 75 has a depressed portion 76 adjacent its end nearest the furnace wall, corresponding to the position of the carriage 12 at which the cleaner element 10 has been inserted to its cleaning position. The flat 70 is so arranged as to make contact with the rail 75 during the movement of the carriage to and from the inserted cleaning position of the cleaner element 10, and to move out of contact with the rail 75 when it (the flat) reaches a position over the depressed portion 76, in which position the collar having the flat 70 thereon is free to turn, and with it the shaft 53 and parts connected therewith including the rotatable head 12 carrying the cleaner element 10.

Means are also included for so controlling the movements and position of the cleaner element 10 and its operating means that an initial and

predetermined angular position of the nozzles is maintained during the insertion and retraction of the cleaner element, and also that the nozzles have a regular and predetermined arc of movement whereby the jets from the nozzles, during the rotation of the cleaner element 10 start from and stop at positions which are predetermined so as always to sweep the desired parts on the inside of the boiler or furnace. This means advantageously comprises a control element 80 (details of which are shown in Figs. 6, 7 and 8), which control element 80 is conveniently made as an irregular casting provided with any suitable means for mounting and fastening it in place, it being advantageously fastened to the track 16, as indicated by numerals 82, 83. This means further comprises a latch-piece 85 capable of turning on a pin 86 projecting from the control element 80, and having a slot 88 through which the pin 86 passes and which permits a limited sliding movement of the latch piece 85 parallel to the face of the control element 80. The latch piece 85 also has a projection 89 which coacts with a stop 91 on the control element 80. The control element 80 has another stop 93 thereon which coacts with the heel 87 of the latch piece 85. The latch piece 85 is also provided with a toe 95 and a notch 97 and a face 99 beveled upwardly from the bottom of the notch, which latter coacts with a projection 100 carried by the cleaner element. The projection 100 is conveniently formed on a collar 102 fitted on the cleaner element 10, and provided with a set screw 104, by means of which the collar may be adjustably positioned and fixed both angularly and longitudinally with relation to the cleaner element 10 and the nozzles thereon. The control element 80 may also be provided with stops 106, 107, which coact with the projection 100 on the cleaner element 10 to limit the rotation of the cleaner element. The control element 80 may also advantageously be provided with an overhanging flange 109 having an opening 111 opposite the notch 97 in the latch piece 85 in the position thereof illustrated in Fig. 6, through which opening the projection 100 on the cleaner element may pass, and behind which overhanging flange 109 the aforesaid projection 100 is held in the longitudinally stopped position of the cleaner element 10 when rotated to either side of the opening 111. The latch piece 85 in conjunction with the projection 100 on the cleaner element 10, and the stops 91 and 93 on the control element 80 control the sequence of turning of the cleaner element in its blowing or cleaning position in a manner which will be described under the caption "Operation."

By adjusting the position of the projection 100 longitudinally of the cleaner element, or the position of the control element 80 on the track 16 toward or from the furnace wall, or both, the position of the cleaner element 10 and of the nozzle 20 thereon may be precisely fixed within the space within the boiler or furnace with relation to the tubes or other parts to be cleaned by the jets from the nozzle. It is important to precisely fix the cleaning position of the cleaner element 10 and the nozzles thereon so as to reach in the most effective manner all parts to be cleaned by the jets. This is especially important in cleaning tubes which constitute the so-called water walls of the boiler.

Means are also advantageously included for opening and shutting off the steam supply from the pipe 60 to the cleaner element 10 automatically through the instrumentality of the mech-

anism employed for inserting and retracting the cleaner element. To this end a cam 113 is mounted over the stem 114 of the valve 62, the valve as here shown, being of the spring closed poppet type. For constructional purposes the cam 113 conveniently acts on the valve stem 114 through an arm or lever 116. The cam 113 may be, as here shown mounted loosely on the shaft 35 to which are attached the sprockets 38. Normally the valve 62 is closed, in which position the cam 113 occupies the position shown in dotted lines, Fig. 4. The mode of operation is for the valve to be opened synchronously with the arrival of the carriage 12 and of the cleaner tube 10 carried thereby, at the blowing or cleaning inserted position of the cleaner element, and this to be effected through the instrumentality of the means for inserting the cleaner element. The steam supply to the cleaner element is also to be shut off through the instrumentality of the inserting and retracting means at the initial operation of the means for retracting the carriage 12. The cam 113 is located in the path of travel of the pin 42 which is carried by the chain 39, and which chain 39 effects the movement of the carriage 12. By the arrangement shown, the pin 42 serves two functions, and thus permits of one pin being used instead of two which could obviously be used were the parts somewhat differently positioned transversely of the track 16. As shown in the drawings, the limit of travel inwardly of the carriage 12 and of the pin 42 which effects movement of the carriage, coincides with a position over the stem 114 of the valve 62. The pin 42 as it approaches the position shown in Fig. 4, picks up the cam 113 and throws it quickly to the position shown in full lines Figs. 4 and 5, thereby bringing about a quick opening of the valve 42. Steam is thus conserved until the cleaner element 10 reaches its cleaning position and is required for blowing on the parts to be cleaned. When the cam 113 is thrown to its valve opening position the pin 42 enters a crotch 118 in the cam. When the retraction of the cleaner element 10 is begun, following the completion of a blowing period, the chain 39 reverses its direction of movement, and the pin 42 in the crotch 118 turns the cam 113 quickly to a position which allows the valve 62 to close under the action of its closing spring. The first part of the movement of the sprocket chain 39 through the pull of the operator on the chain 32 which passes around the pulley 30 has no effect upon the carriage 12, because the pin 42 is able to move in the slot 45 a sufficient distance to move the cam 113 to valve-closing positions before taking up the movement of the carriage 12. This cutting-off of the steam supply to the cleaner element 10 before actual retraction of the carriage 12 and of the cleaner element begins is of great advantage in easing the effort which the attendant must make in retracting the cleaner element. When steam at high pressure is admitted to the cleaner element there is a large force acting on the cleaner element in a direction to oppose its retraction. The cutting off of the steam supply to the cleaner element before the actual retraction of the carriage 12 begins, as just described, relieves the attendant of the necessity of working against the force of the steam in retracting the element 10, and he is required to exert no more effort than that required to insert the cleaner element, which effort is simply that required to overcome the frictional resistance of the parts of its movement.

The inserted position of the cleaner element

10 being adjustable to a limited extent through the means previously described (the adjustment being effected through the control element 80 and the collar 102) it is desirable to correspondingly time the opening and closing of the valve 62 to coincide with the close approach of the cleaner element to its cleaning position. To this end the arm 44 which is attached to the carriage 12 (Figs. 1 to 4) is adjustable on said carriage 12 in the direction of the line of travel of said carriage. To this end the arm 44 may be slotted, as indicated by numeral 129; a screw passing through the slot 129 provides for fastening the arm 44 to the carriage in different positions of adjustment. As the control element 80 acts to stop the cleaner element at an increased distance of insertion (toward the left Fig. 4) the arm 44 is moved correspondingly in the same direction. Adjustments of the position of the arm 44 enables the user to time the opening and closing of the valve to the best advantage with relation to the inserted cleaning position of the cleaner element as determined by the control element 80. The slot 45, together with the adjustability of said arm 44 also enables the cam 113 to operate to cut off the steam supply in advance of the arrival of the pin 42 at the end of the slot 45 where the retraction of the carriage 12 is actually begun.

Operation with particular reference to Figs. 1 to 8 inclusive

Assuming the soot blower to be in its retracted position, shown in Fig. 1 of the drawings, and shown in dotted lines in Fig. 3 of the drawings, the attendant pulls on one of the falls of the pull-chain 32 (the left-hand one in the particular construction illustrated) appropriate to inserting the cleaner element 10 into the space within the boiler or furnace. The rotation of the pulley 30 causes the top flight of the sprocket chain 39 to move toward the left. At this time the valve 62 controlling the supply of steam to the cleaner element 10 through the valve 62 and the gooseneck 65 is shut. For a short distance, or until the pin 42 attached to the chain 39 takes up the slack in moving from the right-hand to the left-hand end of the slot 45 in the arm 44, the carriage 12 is not advanced. When the pin 42 reaches the left-hand end of slot 45, the movement of the carriage to the left, and the insertion of the cleaner element, begins, and the insertion continues until the stop 100 associated with the carriage 12 abuts the control element 80. During the insertion of the cleaner element 10, the cleaner element and the nozzles thereon are maintained in a predetermined angular position through the engagement of the flat 70 on the shaft 53 with the rail 75. The angular position of the cleaner during the insertion insures the clearance of the nozzles between closely spaced tubes, and also insures the start of the blowing being made always from the same desired and predetermined angular position of the nozzles. When the carriage closely approaches the control element 80 the flat 70 passes over the depressed portion 76 of the rail, and in this position the rotatable head 14 mounted in the carriage 12, which carries the cleaner element 10, is free to be turned. Also, as the carriage 12 closely approaches the control element 80 the pin 42 makes contact with the valve cam 113, and quickly throws it from the position shown in dotted lines in Fig. 4 to the position shown in full lines in the same figure, and also in Fig. 5, thereby quickly opening the valve 62 and ad-

mitting steam from the supply pipe 60 to the gooseneck extension 66 telescoping within the cleaner element 10, and remaining lapped or telescoped at the fully inserted position of the cleaner element 10, as illustrated in Fig. 4. A gland 68 maintains a steam-tight connection between the cleaner element 10 and the gooseneck extension 66 during the telescoping movement and also during the rotation of the cleaner element 10 about to be described.

Also, as the carriage 12 closely approaches the inserted blowing position of the cleaner element 10, the projection 100 associated therewith enters the opening in the overhanging flange 109 on the control element 80, contacts with the beveled face 99 on the latch piece 85, and lifts the latch piece on its pivot 86, as best illustrated in Figs. 4, 6 and 7. As previously stated the flat 70 is at this time over the depression 76 of the rail 75, and the projection 100 on the carriage being inwardly beyond the overhanging flange 109 on the control element 80, the cleaner element 10 is now free to be turned, and steam having been admitted to the cleaner element about this same time, the parts of the soot blower are in position for the manipulation of the cleaner element 10 to sweep the inside parts of the boiler with jets of steam to remove soot. In the position just described, the direction and sequence of rotation of the cleaner element 10 is controlled by the latch-piece 85. The cleaner element cannot be turned to the right in Fig. 5, because the projection 100 is within the notch 97 in the latch-piece and the projection 89 on the latch-piece abuts the stop 91 on the control element 80. When the attendant pulls on the chain 51 to rotate the cleaner element 10, he must pull on the fall (operating through the worm 57 and gear 59) which will turn the cleaner element 10 in a left-hand or counterclockwise direction, Fig. 6. The cleaner element 10 can now turn, because the projection 89 can be moved away from the stop 91, the projection 100 and the notch at the lower portion of the latch-piece 85, which move in diverging arcs, allowing the projection 100 to move out of the notch 97 as the latch-piece swings to the left. Continued pull on the appropriate fall of the chain 51 will produce a rotation of the cleaner element 10 through as many angular degrees as desired to approximately 360°. In the embodiment shown, however, two stops 106, 107 are provided which limit the angle of rotation of the cleaner element 10 to 180°, 90° on each side of the position shown in Fig. 6. The pulling of the chain 51 continues the rotation of the cleaner element 10 until the projection 100 meets the stop 106. When this occurs the attendant grasps the opposite fall of the chain 51 and pulls on this. This rotates the cleaner element in a clockwise direction, the projection 100 moving away from the stop 106. As the projection 100 approaches the latch 85 it contacts the heel 87 of the latch. The latch 85 having dropped down on its pin 86 after the projection 100 left the notch 97 on the previous counterclockwise rotation of the cleaner element, the projection 89 on the latch-piece 85 is in a position to clear the stop 91. Consequently when the projection 100 strikes the heel 87 of the latch 85, the latch is free to swing to the right and to allow the projection 100 to pass in a clockwise direction, as illustrated in full lines in Fig. 8, and in dotted lines in Fig. 6. The rotation of the cleaner element can continue until further clockwise rotation is prevented by contact between the

projection 100 and stop 101. The cleaner element cannot be retracted in this position, or in any position other than that in which the projection 100 is opposite the opening 111, because the said projection 100 is overhung by the flange 109 on the control element 80. Consequently the attendant is compelled to reverse the direction of rotation of the cleaner element. This he does by grasping the fall of the chain 51 which he first used, and a counterclockwise direction of rotation is imparted to the cleaner element 10. This latter counterclockwise direction of rotation continues until the projection 100 strikes the nose 95 of the latch 85. After this contact the counterclockwise direction of rotation is continued until the heel 87 of the latch-piece strikes the stop 93 on the control element 80. At this time the nose 95 limits the counterclockwise rotation of the cleaner element and the projection 100 associated therewith at a position in front of the opening 111 in the overhanging flange 109. Then the carriage 12 and the cleaner element 10 are in a position to be retracted. The angular position of the cleaner element when retraction is begun is the same as it was when insertion ended, and the flat 70 is thereby in position to ride onto and over the rail 75, these latter parts maintaining the position of the cleaner element 10 and its operating mechanism after the projection 100 leaves its position behind the overhanging flange 109. As the projection 100 leaves the opening 111 the latch-piece 85 swings to the position where the notch 97 therein is in line with the opening 111, and the latch-piece is down on its pin 86, in position for functioning as hereofore described on a repetition of the insertion and cleaning use of the cleaner element 10. The retraction of the carriage 12 and of the cleaner element 10 carried thereby is effected by the attendant pulling on the appropriate fall of the chain 32 (the righthand fall in the embodiment illustrated in Fig. 1). The initial rotation of the pull in the direction to retract the carriage 12 does not act on the carriage, because the pin 42 has a slack movement as it runs from the left-hand end of the slot 45 in arm 44 to the right-hand end. During this movement of the pin 42 from the left-hand end to the right-hand end of the slot 45, the important effect of shutting off the supply of steam to the cleaner element 10 is effected. Upon the completion of the rotation of the cleaner element 10, as has previously been described, the carriage 12, sprocket chain 39, pin 42 thereon, the valve cam 113, and the valve are in the positions illustrated in full lines Figs. 4 and 5. The pin 42 is in the crotch 112 in the valve-cam 113. As the pulley 39 is turned to retract the carriage 12 during the first part of this retracting movement, while the projection 100 is moving away from the control element 80 through the opening 111, and while the pin 42 is moving idly in the slot 45 in the arm 46, the valve-cam 113 is thrown quickly to valve-closing position. The valve-closing position is illustrated in dotted lines Fig. 4. The result of the closing of the valve 62 in this manner is to shut off the supply of steam to the cleaner element 10 prior to any effort being exerted by the attendant in retracting the carriage 12 and the cleaner element 10 carried thereby. The resistance to the retraction of the carriage 12 due to the action of steam under pressure in the cleaner element 10 is thus avoided. The actual retraction of the carriage 12 is only begun when the pin 42 reaches the right-hand end of the slot

45 in arm 44, and, as previously stated, after the valve-cam 113 has been thrown to valve-closing position. Continued pull of the attendant on the chain 32 effects the retraction of the carriage 12 with slight exertion on his part from the inserted blowing position of the cleaner element 10 to its fully retracted position, which fully retracted position is illustrated in Fig. 1.

As previously described the cleaner element 10 and the nozzles thereon may be precisely located longitudinally at their inserted blowing position by adjustment of the control element 80 toward or from the boiler wall, or by similar movement of the collar 102 which carries the projection 100 (or by adjustments of both). By such precise positioning of the cleaner element 10 and its nozzle or nozzles, important results in obtaining maximum cleaning efficiency are obtained. The slot 129 in the carriage arm 44 enables the carriage arm to be adjusted in relation to the adjustments of the control element 80 and projection 100, so as to maintain the desired timing of the admission and shutting-off of steam to the cleaner element 10 with relation to the close approach to and departure from the inserted blowing position of the cleaner element 10 and of the carriage 12 which carries the latter.

Referring now to the embodiment illustrated in Figs. 9 to 16 inclusive, and Fig. 20, which embodies the mechanical and functional principles of the embodiment of Figs. 1 to 8 inclusive described in the preceding part of the specification, corresponding reference numerals will be used for corresponding parts.

Numeral 10 designates the cleaner element, 12 the carriage, and 14 a rotatable head mounted on the carriage and attached to the outer or right-hand end of the cleaner element 10, as best shown in Fig. 13. The carriage 12 moves back and forth on a track 16 to insert the cleaner element into and retract it from the space within the boiler or furnace containing the parts to be cleaned. The track 16 is conveniently in the form of a pair of channel beams, as shown, and the carriage 12 may be supported and guided therein by a set of flanged rollers 17. The cleaner element 10 is provided with one or more nozzles for directing jets of steam on to the parts to be cleaned, a plurality of nozzles 20 being here shown.

Numeral 22 designates an opening in the furnace wall through which the cleaner element is inserted and retracted and the space between the cleaner element 10 and the sleeve may be closed by an annulus 27. A hinged lid 130 may be provided for completely covering the opening 22 in that form of the embodiment where the cleaning element is entirely retracted or withdrawn from the boiler or furnace. The soot blower is attached to the boiler or furnace adjacent the opening 22 in any suitable manner. As here shown, it may be attached by means of a bracket 24 of built-up structural steel shapes bolted or otherwise secured alongside of the side wall of the furnace. Additional means of support, not shown, such as hanger rods, may be provided for giving additional support to the soot blower.

Means for moving the carriage 12 to insert the cleaner element into and retract it from the space within the boiler is included. This means comprises a pulley 30 over which passes an endless pull-chain or the like. The pulley 30 is attached to a shaft 35 mounted in a suitable part of the supporting bracket 24. The shaft 35 has fixed thereon a sprocket wheel 38 around which passes

a sprocket chain 39, and near the opposite end of the track there is mounted in any suitable manner, another sprocket wheel 40 around which the sprocket chain 39 also runs, so that the chain 39 has a flight parallel to the track 16. The carriage 12 is operatively connected to the carriage moving means by means of a pin or pins on the sprocket chain 39 coacting with a part on the carriage in such manner that lost motion between the sprocket chain and the carriage is provided in certain parts of the movement of the sprocket chain. As here shown, the sprocket chain 39 is provided with a pair of spaced pins 42, 42a which make contact with opposite sides of a part 44 of the carriage, the pins 42, 42a being spaced apart a greater distance than the width of the part 44.

Means are provided for rotating the rotatable head 14 and the cleaner element 10 fixed thereto, by which the cleaner element 10, when inserted into the space within the boiler, may be turned so that the jets which issue from the nozzle on the cleaner element may be caused to appropriately play on the parts to be cleaned. This means may comprise a pulley 50 having thereon a suitable pull chain or the like, 51.

In the present embodiment the pulley 50 is not carried by the carriage, as in the first described embodiment, but has a splined connection therewith through a squared shaft 140 or the like. The pulley 50 may be located adjacent either end of the track 16, as illustrated in full lines and in dotted lines Fig. 10. The carriage has a pinion 142 having a hub 144 mounted on the carriage and having a splined connection with the squared shaft 140, in such manner that the pinion 142 moves with the carriage 12, and is rotatable through the squared shaft 140 in predetermined longitudinal positions of the carriage 12. The rotatable head 14 has a gear 148 thereon and has a driving connection with the pinion 142, the driving connection, as here shown, being through reducing gears 150 and 151.

Steam is supplied to the cleaner element 10 from a supply pipe 60 through a valve 62 and a gooseneck 65 having an extension 66 which extends within the cleaner element 10 so as to telescope therewith, and remain lapped or telescoped with the element in its position of farthest insertion within the boiler. A steam-tight connection between the extension 66 and the rotatable head 14 is effected by means of a suitable gland or packing 68.

Means are also included for preventing rotation of the rotatable head 14 while the cleaner element 10 is being moved to and from its inserted cleaning position. In the present embodiment the control means is contrived to effect control at a plurality of inserted cleaning positions.

This means advantageously comprises a rail 75 which, in the present embodiment, is one of the flanges on the channel bar which functions as the track 16, and a part 160 associated with the means for rotating the cleaner element 10 in its inserted blowing positions. The said part 160 may have the form of a disc fastened to the rotary head 14. The disc 160 has a notch 161 into which the rail 75 extends, which parts coact to prevent rotation of the rotary head, and thereby of the cleaner element 10, in the retracted position of the cleaner element, and in other positions of the head which do not coincide with one or another of the inserted blowing positions of the element 10. At each of the inserted blowing positions of the cleaner element 10, the rail is

provided with a notch 163 which, when the disc 160 is opposite the notch 163, allows the rotatable head 14 to which it is connected, to rotate in a controlled manner soon to be described. As shown in the drawings, there are three inserted blowing positions of the cleaner element 10, best shown in Figs. 10 and 11, and designated by the letters A, B and C. For each of these inserted blowing positions there is a control element 80.

Means are also included for so controlling the movement and position of the cleaner element 10 and its operating means that an initial and predetermined angular position of the nozzles is maintained during the insertion and retraction of the cleaner element, and also that the nozzles have a regular and predetermined arc of movement whereby the jets from the nozzles during the rotation of the cleaner element 10 start from and stop at positions which are predetermined so as always to sweep the desired parts on the inside of the boiler or furnace. This means comprises a control element 80 one of which is provided for each of the inserted blowing positions of the element 10, there being three of these designated by the letters A, B and C, in the embodiment illustrated, as previously stated. The control elements 80 are pivoted on pins 165, which are conveniently in the form of bolts which pass through holes in the track 16, and by suitably positioning these holes with reference to the location of the cleaner element 10 within the boiler, precise positioning of the cleaner elements with relation to the boiler parts to be cleaned, may be obtained. The control element 80 has an arm 167 which normally stands in the path of a projection 100 carried by the rotary head 14. In the construction illustrated the projection 100 is formed on the disk 160 which is attached to the said rotatable head 14. The rotation of the rotary head 14 and of the cleaner element 10 carried thereby, the direction of rotation and angular sweep, and the starting and ending position of the cleaner element 10 and of the nozzles thereon in their arc of movement, are controlled by the coaction of projection 100 on disk 160 with a projection 170 on the arm 167 of control element 80, and a stop 171 on the track 16 which coacts with the arm 167 of control-element 80. This manner of coaction will be described subsequently under the caption "Operation."

Means are also advantageously included for opening and shutting off the steam supply from the pipe 60 to the cleaner element 10 automatically through the instrumentality of the mechanism employed for inserting and retracting the cleaner element. The construction in the present embodiment is very similar to that of the first embodiment, and comprises a cam 113 mounted over the stem 114 of the valve 62, the valve being similar to that illustrated and described with reference to Fig. 5. As previously described, the cam 113 may act on the stem 114 through an arm or lever 116. The cam 113 is mounted loosely on a pin or shaft 175. The cam also has thereon a finger 177 through which it is operated in a manner to be immediately described. Normally the valve 62 is closed, in which position the cam 113 occupies the position shown in full lines Fig. 9, with the finger 177 thereon projecting toward the left in said figure. The mode of operation is for the valve 62 to be opened synchronously with the arrival of the carriage 12 and of the cleaner element 10 carried thereby at the blowing or cleaning position of the cleaner element, or, where there are a plurality of blowing posi-

tions as in the present embodiment, at the first blowing position, this to be effected through the instrumentality of the means for inserting the cleaner element. The steam supply of the cleaner element 10 is also to be shut off through the instrumentality of the inserting and retracting means at the initial operation of the means for retracting the carriage 12, which shutting-off would be done at the last blowing position in this embodiment having a plurality of blowing positions. The sprocket chain 39 which is driven from the pulley 30, and which is operatively connected to the carriage 12, carries a valve opening pin 180 and a valve closing pin 181, best shown in Figs. 9 and 10. The finger 177 on the valve-cam 113 is located in the path of travel of these pins 180, 181. The pin 180 is so located on the sprocket chain 39, that it makes contact with the finger 177 as the carriage 12 closely approaches the first control-element 80 at the first cleaning position indicated by reference letter A. As the operator continues to pull on the pull-chain 32 from this position of close approach of the carriage 12 to the first control-element 80, the pin 180 on chain 39 throws the valve-cam 113 over to the position shown in full lines in Fig. 16, and by the time the projection 100 on the carriage meets the arm 167 of the first control-element 80, valve 62 has been opened, steam supplied to the cleaner element 10 through the gooseneck 65 and extension 66, and the pin 180 has passed beyond the cam-finger 177 as shown Fig. 16. The description will continue with particular reference to the valve operation, after which the description will return to the operations which occur after the valve has been opened and the carriage 12 has been stopped at the first blowing position and the related structure. When the operator pulled the pull-chain 32 to advance the carriage 12 to the first cleaning position, the pin 180 struck the finger 177 in its right-hand position Fig. 16, and depressed it slightly to the position shown in dotted lines and designated 177a, which depressed position allowed the pin 180 to pass on, after which the cam-piece 113 righted itself restoring the finger 177 to the position shown in full lines Fig. 16. Just prior to the carriage 12 reaching the last blowing position C, Fig. 11, and just before the projection 100 associated with the carriage 12 meets the last control-element 80, the pin 181 passes over the finger 177, depressing it to the position shown in dotted lines 177a, the valve-cam 113 righting itself and restoring the finger to the full line position, Fig. 16. With the pin 181 on sprocket chain 39 slightly beyond the finger 177 (in about the position of the pin 180 on Fig. 16 of the drawings), when the operator pulls on the pull-chain 32 in a direction to retract the carriage, the pin 181 on the sprocket chain is immediately brought against the finger 177 of valve-cam 113, and a slight additional movement of the chain 39 serves to quickly throw the finger 177 to the full-line position illustrated in Figs. 9 and 10, and the dotted line position indicated by the numeral 177b Fig. 16, thus producing a shutting off of the steam supply to the cleaner element 10. During this shutting action of the retracting means on the valve 62 there has been a loss of motion between the retracting means and the carriage 12 by reason of the spacing of the pins 42 and 42a with reference to the part 44. After the valve has been shut as just described, the pin 42 has moved from the position shown in Fig. 13 to the position

shown in Fig. 9, that is, in contact with the arm 44 and in position to transmit the motion of the sprocket chain 39 to the carriage 12. With the steam thus shut off, the retraction of the cleaner element is completed by the attendant pulling on the proper fall of the pull-chain 32 to retract the cleaner, the exertion of the attendant in retracting the cleaner element being simply that required to overcome the friction of the parts, the attendant being relieved of the effort which would be required to retract the carriage against the resistance produced by the action of the steam in and flowing from the cleaner element 10. The pins 180, 181 may be placed at suitable locations on the chain 39, and their locations thereon may be changed, to correlate the opening and shutting of the valve 62 to the close approach to the appropriate control elements 80 which determine the inserted blowing positions of the cleaner element 10 at which the valve is to be opened and shut.

At each of the inserted blowing positions of the cleaner element 10 (as for example at each of the positions A, B, C of Fig. 11) the disk 160 which in conjunction with the rail 75 prevents rotation of the rotatable head 14, except when the carriage 12 and the cleaner element 10 carried thereby are in blowing position, in each of these blowing positions is free to be rotated by reason of the notches 163 in the rail 75 being opposite the control elements 80. When the carriage 12 is in a blowing position A, B or C, and the projection 100 associated with the carriage is in contact with one of the control elements 80, the attendant pulls on the proper fall of the chain 51 to rotate the rotary head 14. The direction of rotation is determined by the control means constituted by the projection 100, control element 80, projection 170 and stop 171. The angular position to and from which the rotatable head moves is also controlled by these same parts, and said position is preserved during retraction by the action of the rail 75 and the notched disk 160, heretofore referred to. The angular width of the projection 100 together with that of notch 161 determines the arc of rotation of the rotatable head 14 and of the cleaner element 10 carried thereby. When, in the embodiment illustrated, the attendant pulls on the pull-chain 51, he can only begin to pull in one direction, viz., in a counterclockwise direction indicated by the arrow on Figs. 14 and 15. By pulling on the proper fall of the chain 51, the operator can continue to rotate the head 14 until the projection 100 strikes the top of projection 170 on control element 80. This causes the control element 80 to swing on its pivot and the arm 167 thereon to be brought against stop 171. Thereafter the turning of the rotary head in a counterclockwise direction will be prevented. The head 14 and the cleaner element 10 are now stopped in their angular starting position, which is the position shown in Fig. 14. The parts of the rotation control-means are now in position to allow the cleaner element 10 and its carriage 12 to be further inserted, or retracted, as the case may be.

Operation with particular reference to Figs. 9 to 16 inclusive

Assuming the soot blower to be in its retracted position, shown in Figs. 9 and 10 of the drawings, the attendant pulls on one of the falls of the pull-chain 32 (the left-hand one in the particular construction illustrated) appropriate to

inserting the cleaner element 10 into the space within the boiler or furnace. The rotation of the pulley 39 causes the top flight of the sprocket chain 39 to move toward the left. At this time the valve 62 controlling the supply of steam to the cleaner element 10 through the valve 62 and the gooseneck 65 is shut off. The chain 39 moves idly for a short distance, until the pin 42a takes up the slack between it and the part 44 of the carriage. After the pin 42a contacts with the part 44 of the carriage, the cleaner-tube-inserting-movement of the carriage 12 is taken up and continued as the attendant continues to rotate the pulley 39 until the projection 100 associated with the head 14 makes contact with the control element 80 at blowing position A, Fig. 11. Just previous however to the projection 100 meeting the control element 80, the pin 180 on sprocket chain 39 has made contact with the finger 177 on valve-cam 113, and in the short approach of the carriage-projection 100 to the control element 80 the pin 180 on the chain 39 throws the arm 177 from the position shown in full lines Fig. 9 to the position shown in full lines Fig. 16, thereby effecting a quick opening of the valve 62 through the action of the valve-cam 113. The attendant then proceeds to rotate the cleaner element, which rotation, during insertion, and until the disk 160 on the rotatable head 14 reaches a position opposite the notch 163 in the rail 75, is prevented by the projection of the rail 75 into the notch 161 of the said disk 160. With the projection 100 associated with the head 14 against the first control element 80, the attendant pulls on the fall of pull-chain 51 which yields to his pull, and which is appropriate to the control of the direction of rotation of the head 14 effected by the mechanism in the illustrated embodiment. By pulling on the appropriate fall of chain 51, the attendant produces rotation of the head 14 and of the cleaner element 10 (through the square shaft 140, pinion 142 and gears 150, 151 and 148) in a counterclockwise direction, and this counterclockwise rotation is continued until the projection 100 associated with the head makes contact with the projection 170 on the arm 167 of control-element 80 and said arm makes contact with the fixed stop 171. Thereafter a pull on chain 151 can no longer produce counterclockwise rotation of the cleaner element 10. In this stopped position the cleaner element has been returned to the same angular position as that at which rotation thereof to effect cleaning was started, the angle of rotation with the illustrated embodiment being 360°.

The attendant is now ready to advance the cleaning element to its second blowing position. He thereupon grasps the pull-chain 32 and pulls on the fall thereof to turn the pulley in a direction to advance the head and the carriage 12 to the blowing position B, Fig. 11. The carriage is capable of advancing at this time because the projection 100 associated with the head has contacted with the projection 170 of the control-element 80 and depressed the arm 167 out of the path of said projection 100.

When the projection 100 associated with the head 14 makes contact with the second control-element 80 (position B, Fig. 11) the carriage 12 and the cleaner element 10 carried thereby is stopped in the second blowing position, and the operator pulls on the appropriate fall of chain 51 to rotate the head 14 and the cleaner element 10, the direction of rotation and the stopping of the rotation being effected in a manner similar to

the operation described with reference to the parts in the first blowing position.

The attendant then proceeds to advance the carriage 12 to bring the cleaner 10 to the third and last of the illustrated blowing positions (position C, Fig. 11). As the carriage 12 closely approaches the control-element 80 at this position C, the pin 181 on the sprocket chain 39 makes contact with the cam-finger 177 and during the interval of close approach passes beyond said cam-finger 177, the said finger during the passage of the pin 181 depressing slightly to the position indicated in dotted lines 177a, Fig. 16 and then returning to the position shown in full lines in said figure. When the projection 100 associated with the head 14 meets the third and last control-element 80, the attendant grasps the appropriate fall of pull-chain 50 and rotates the cleaner element 10, the direction of rotation, and the stopping point of the element 10 in its arc of rotation being controlled by the projection 100, control-element 80, projection 170 and stop 171, the operation of these and the other related parts being as previously described.

The attendant after completing the cleaning at the third blowing position (position C), then proceeds to retract the cleaner element 10 so as to withdraw it from the interior of the boiler or furnace. He then proceeds to do so by pulling on the fall of the pull-chain 32 which will produce clockwise rotation of the pulley 39 in the embodiment illustrated. The first thing which occurs is that the pin 181 lying at this time just beyond the cam-finger 177, makes contact with said cam-finger and by a short movement throws the cam-finger 177 and the valve-cam 113 to the position shown in dotted lines 177b, Fig. 16, and in full lines Fig. 9, thereby effecting a quick shutting of the valve 62. During this travel of the sprocket chain 39 while the valve 62 is being shut, no motion of the carriage 12 is produced, because during this short movement of the chain 39 the pin 42 thereon has been taking up the slack between it and the part 44 of the carriage. When the pin 42 makes contact with the part 44 of the carriage, after the valve has been shut, continued pull on the pull-chain 32 causes the carriage 12 to be moved in a direction to retract the cleaner element 10, that is, toward the right in Figs. 9 and 10 of the drawings. As the sprocket chain 39 moves in a direction to retract the carriage 12, the pin 181 which acted to throw the valve-cam 113 to closing position, slightly depresses the cam-finger 177 from the position shown at 177b, Fig. 16 to the position shown in dotted lines at 177c, and, after the pin 181 has passed, the cam-finger 177 is returned to the position shown in dotted lines at 177b. The position 177b, Fig. 16, corresponds to the position shown in full lines Fig. 9. The attendant in retracting the carriage 12 therefore needs to exert only sufficient effort to overcome the frictional resistance of the parts, and is relieved of the very considerable force which would be opposed to the retraction if steam under pressure were flowing in the cleaner element and issuing from the nozzles thereon. During the retraction of the carriage 12, the projection 100 associated therewith strikes against the rear of the arms 167 on control-elements 80, depressing these arms 167, and thereby allowing the carriage 12 to be retracted without being opposed by the said control elements 80. The attendant continues to pull on the pull-chain 32 until the cleaner element 10 is fully retracted, that is, either with-

drawn through the opening 22, or its end housed and protected in the recess formed by said opening 22, the fully retracted position being illustrated, Fig. 9 of the drawings. The fully inserted position of the carriage 12 is illustrated in dotted lines in said figure. The blowing positions A, B and C, Fig. 11 of the cleaner element 10 may be precisely determined by carefully locating the holes in the channel bar constituting the track 16.

As previously stated, the invention further provides an improved cleaner-element, illustrated in Figs. 17, 18 and 19. In large boilers having high steam generating capacity, particularly in certain parts thereof, the temperature is very high—sufficient to soften unsupported steel pipes containing steam and no water. As the position of the nozzles is important to the obtaining of high cleaning efficiencies, and as the spacing of boiler tubes often is close, it is highly important to maintain the cleaner elements 10 straight and true. The present invention provides a cleaner element which remains virtually straight and true even without supports notwithstanding high temperatures in certain parts of boilers heretofore mentioned. Referring to Figs. 17 and 18, numeral 10 illustrates part of the cleaner element, sufficient to illustrate the improvement. Numerals 20 indicate nozzles carried by the cleaner element 10. Within the tubular element 10 a second tubular element 200 is fitted. This inner tubular element 200 is provided with projections 202 which contact with the inner wall of the tubular element 10, and leave steam spaces 205 between the inner tube 200 and the outer tube 10 around the same. This inner tube 200 is open at each end, as indicated at 207 and 208, so that steam may flow from end to end of the tubular element 10 both on the inside and on the outside of the tube 200. The tubular part 200 is also advantageously provided with holes or openings 209 opposite the nozzles 20, as illustrated.

As illustrated in Figs. 17 and 18, the projections 202 may be provided by the cross-sectional form of the inside tube 200, the said inside tube in this embodiment being illustrated as square in cross-section, the projections being provided by the corners of the square tube, which contact with the inner surface of the tubular cleaner element 10.

In another embodiment illustrated in Fig. 19, the inside tube 200a may be round in cross-section. It has an outside diameter substantially less than the inside diameter of the tubular element 10, providing steam spaces 205 around the inside of tubular element 10, and running the length thereof, the tube 200a being open at its ends, and may otherwise have the structural features of the embodiment illustrated in Figs. 17 and 18. The projections 202, in the form of embodiment shown in Fig. 19, may, as illustrated, be longitudinally extending ribs attached to either the inner tube 200a or the tubular element 10 which make contact between the outer surface of the inner tube 200a and the inner surface of the tubular element 10.

The inside diameter, or dimensions, of the square tube 200 illustrated in Figs. 17 and 18, and of the round tube 200a illustrated in Fig. 19 slightly exceeds the outside diameter of the gooseneck extension 68 which telescopes within the tubular cleaner element 10, to provide for such telescoping when the said cleaner element 10 is inserted into or retracted from a boiler, the out-

side diameter of the gooseneck extension 68 being shown by the dotted circle, Figs. 18 and 19.

When the cleaner element 10 is used for cleaning within a boiler or furnace, steam flows through the same and escapes in jets from the nozzle or nozzles therein. The steam used for cleaning, having access to the spaces 205 at one or both ends 207, 208 of the inner tube 200 (200a) as may be desired, insulates the inner tube track 200, or 200a from the extreme heat within the boiler or furnace to which the tubular cleaner element 10 is exposed, and while the tubular cleaner element 10 may be heated sufficiently high to soften it, the temperature of the inner tube 200, 200a, cannot much exceed the temperature of the steam flowing in the spaces 205 between the tubes and insulating the inner tube 200, 200a. Of course the steam flowing into the tube 200, 200a, also acts to absorb heat so as to counteract any rise in temperature, over that of the steam, of the said tube 200, 200a.

Owing to the difference in temperature between the tubes 10 and 200 there is a difference in expansion of the tubes in use, and the construction should allow for such differential expansion. The tube 200 may be attached at one end to the tube 10 as indicated at 212, as by means of a weld, such mode of connection permitting of differential expansion.

The inner tube 200, 200a, being thus insulated by the steam from extreme temperatures within the boiler or furnace, preserves its rigidity, and thereby its true ness or alinement, and, being in contact with the outer tubular cleaner element 10 through the projections 202, prevents the tubular cleaner element 10 from losing its true ness or alinement, despite the fact that it may be unsupported and may be heated to a temperature which softens it.

The invention may receive other embodiments than those herein specifically illustrated and described.

What is claimed is:

1. A soot-blower of the retractable type comprising a cleaner element, a track, a carriage movable on said track, a rotatable head on said carriage to which said cleaner element is attached, means for moving said carriage on said track to insert the cleaner element in and retract it from an operating position, means mounted on said carriage for rotating said rotatable head, and means for preventing rotation of said rotatable head while said cleaner element is being moved to and from its inserted cleaning position.

2. A soot-blower according to claim 1, wherein said rotation preventing means comprises a rotatable part having a flat thereon connected to said rotatable head, and a rail arranged to contact with said flat in the movements of the carriage to and from the inserted position of the cleaner element and having a depression at the position of said rotatable part having the flat thereon corresponding to an inserted cleaning position of said cleaner element, which permits said rotatable part to turn and said means for rotating said rotatable head to be turned.

3. A soot-blower according to claim 1, wherein said rotation preventing means comprises a rotatable disk connected to said rotatable head, a rail running lengthwise of said track, and means on said disk contacting said rail in the movements of said carriage to and from the inserted position of the cleaner element, said rail having a notch at a position corresponding to a clean-

ing position of said cleaner-element which permits said rotatable part to turn and said means for rotating said rotatable head to be turned.

4. A soot-blower of the retractable type comprising a cleaner-element, a track, a carriage, movable on said track, by which said cleaner element is carried, means for moving said carriage on said track to insert the cleaner element in and retract it from an operating position, comprising a connection providing a limited lost-motion between said carriage moving means and the carriage, a valve for admitting and shutting off a supply of steam to said cleaner element, and means for opening and shutting said valve comprising a part connected to said carriage moving means and a part at a position corresponding to an inserted cleaning position of said cleaner element, said parts being constructed and arranged to automatically shut said valve through the intermediary of said carriage-moving-means at an inserted cleaning position of said cleaner-element before motion is taken up between said carriage and carriage moving means and retraction of the cleaner element begins.

5. A soot-blower of the retractable type comprising a cleaner-element, a track, a carriage movable on said track, a rotatable head on said carriage to which said cleaner-element is attached, means for moving said carriage on said track to insert the cleaner-element in and retract it from an operating position, comprising a connection providing a limited lost-motion between said carriage moving means and the carriage, means for rotating said rotatable head, means for preventing rotation of said rotatable head while said cleaner-element is being moved to and from its inserted position, a valve for admitting and shutting off a supply of steam to said cleaner-element, and means for opening and shutting said valve comprising a part connected to said carriage-moving-means and a part at a position corresponding to an inserted cleaning position of said cleaner-element, said parts being constructed and arranged to automatically shut said valve through the intermediary of said carriage-moving-means at an inserted cleaning position of said cleaner-element before motion is taken up between said carriage and carriage moving means and retraction of the cleaner element begins.

6. A soot-blower of the retractable type comprising a cleaner-element, a track, a carriage, movable on said track, means for moving said carriage on said track to insert the cleaner-element in and retract it from an operating position comprising a connection providing a limited lost motion between said carriage-moving-means and the carriage, a valve for admitting and shutting off a supply of steam to said cleaner-element, and means for opening and shutting said valve comprising a part connected to said carriage-moving-means and a part at a position corresponding to an inserted cleaning position of said cleaner element, said parts being constructed and arranged to open said valve through the intermediary of said carriage-moving-means at a position corresponding closely to an inserted cleaning position of said cleaner-element and to automatically shut valve through the intermediary of said carriage-moving-means while said carriage is at an inserted cleaning position of said cleaner element and before said carriage-moving-means has completed the lost motion

between it and said carriage and begins the retraction of said carriage and cleaner element.

7. A soot-blower of the retractable type comprising a cleaner-element, a track, a carriage, movable on said track, a rotatable head on said carriage to which said cleaner element is attached, means for moving said carriage on said track to insert the cleaner-element in and retract it from an operating position comprising a connection for providing a limited lost motion between said carriage-moving-means and the carriage, means for rotating said rotatable head, means for preventing rotation of said rotatable head while said cleaner-element is being moved to and from its inserted position, a valve for admitting and shutting-off a supply of steam to said cleaner-element, and means for opening and shutting said valve comprising a part connected to said carriage-moving-means and a part at a position corresponding to an inserted cleaning position of said cleaner-element, said parts being constructed and arranged to open said valve through the intermediary of said carriage-moving-means at a position corresponding closely to an inserted cleaning position of said cleaner-element and to shut said valve through the intermediary of said carriage-moving-means while said carriage is at an inserted cleaning position of said cleaner-element and before said carriage-moving means has completed the lost motion between it and said carriage and begins the retraction of said carriage and cleaner-element.

8. A soot-blower of the retractable type comprising a cleaner-element, a track, a carriage, movable on said track, a rotatable head on said carriage to which said cleaner-element is attached, means for moving said carriage on said track to insert the cleaner-element in and retract it from an operating position, means mounted on said carriage for rotating said rotatable head, and means for controlling the direction of rotation of said rotatable head.

9. A soot-blower of the retractable type, comprising a cleaner-element, a track, a carriage, movable on said track, a rotatable head on said carriage to which said cleaner-element is attached, means for moving said carriage on said track to insert the cleaner-element in and retract it from an operating position, means mounted on said carriage for rotating said rotatable head, means for controlling the direction of rotation of said rotatable head, and means for preventing rotation of said rotatable head while said cleaner element is being moved to and from its inserted cleaning position.

10. A soot-blower of the retractable type comprising a cleaner-element, a track, a carriage, movable on said track, a rotatable head on said carriage to which said cleaner element is attached, means for moving said carriage on said track to insert the cleaner element in and retract it from an operating position comprising a connection for providing a limited lost motion between said carriage-moving-means and the carriage, means for rotating said rotatable head, means for controlling the direction of rotation of said rotatable head, means for preventing rotation of said rotatable head while said cleaner-element is being moved to and from its inserted cleaning position, a valve for admitting and shutting off a supply of steam to said cleaner element, and means for opening and shutting said valve comprising a part connected to said carriage-moving-means and a part at a position corresponding to an inserted cleaning position of said

cleaner-element, said parts being constructed and arranged to open said valve through the intermediary of said carriage-moving-means at a position corresponding closely to an inserted cleaning position of said cleaner-element and to shut said valve through the intermediary of said carriage-moving-means while said carriage is at an inserted cleaning position of said cleaner-element and before said carriage-moving-means has completed the lost motion between it and said carriage and begins the retraction of said carriage and cleaner element.

11. A soot-blower of the retractable type comprising a cleaner-element, a track, a carriage movable on said track, a rotatable head on said carriage to which said cleaner-element is attached, means for moving said carriage on said track to insert the cleaner-element in and retract it from an operating position, means mounted on said carriage for rotating said rotatable head, and a control element at a position corresponding to an inserted cleaning position of said cleaner-element, coacting with a part attached to said rotatable head and having means coacting therewith for stopping said carriage and cleaner-element carried thereby at a precise inserted cleaning position for controlling the direction of rotation of said cleaner-element at its aforesaid inserted cleaning position.

12. A soot-blower of the retractable type comprising a cleaner-element, a track, a carriage movable on said track, a rotatable head on said carriage to which said cleaner-element is attached, means for moving said carriage on said track to insert the cleaner-element in and retract it from an operating position, means mounted on said carriage for rotating said rotatable head, a control element at a position corresponding to an inserted cleaning position of said cleaner-element, coacting with a part attached to said rotatable head, and having means coacting therewith for stopping said carriage and cleaner-element carried thereby at a precise inserted cleaning position and for controlling the direction of rotation of said cleaner-element at its aforesaid inserted cleaning position, and means for preventing rotation of said rotatable head while said cleaner-element is being moved to and from its stopped inserted cleaning position.

13. A soot-blower according to claim 11, wherein said control-element comprises a plate, a part pivotally mounted thereon, and stops limiting the movement of said pivoted part, said pivoted part together with said stops, and coacting with said part on the rotatable head to control the direction of rotation of said rotatable head within limits on both sides of the starting position.

14. A soot-blower according to claim 11, wherein said control element comprises a plate, a part pivotally mounted thereon, stops limiting the pivotal movement of said pivotal part, said pivotal part having a slot which admits of vertical movement thereof, a notch and a beveled face within said notch, said pivotal part coacting with said coacting part on the rotatable head to first lift said pivotal part to bring it against one of said stops to limit rotation in one direction, said coacting part on the rotatable head on its reverse direction of rotation contacting with said pivotal part in its down position, in which the pivotal part is clear of said first-named stop, and permitting rotation to proceed in the reverse direction, said coacting part on the cleaner element, on resuming its original direction of rotation, contacting with said pivotal part and

another of said stops which limit the movement of said pivotal part to stop said rotatable head at its initial position.

15. A soot-blower according to claim 11, wherein said control-element comprises a plate, a part pivotally mounted thereon, and stops limiting the movement of said pivoted part, said pivoted part together with said stops, coacting with said part on the rotatable head to control the direction of rotation of said rotatable head, and means for limiting the degree of angular rotation of said rotatable head when it is free to be rotated.

16. Apparatus according to claim 11, wherein said control-element comprises a pivotal part and stops limiting its pivotal movement, said pivotal part having an arm which normally projects into the path of movement of said coacting part on the rotatable head, and, in said position, acts to stop the insertion-movement of said rotary head at a cleaning position, said part on said rotatable head, when rotated, contacting with the rear of said arm and depressing it, in which latter position said rotatable head and the coacting part thereon can clear said control element and be moved to a cleaning position at greater insertion within the space in the boiler.

17. A soot-blower according to claim 11, wherein said control element comprises a pivotal part and stops limiting its pivotal movement, said pivotal part having an arm which normally projects into the path of movement of said coacting part on the rotatable head, and, in said position, acts to stop the insertion-movement of said rotary head at a cleaning position, said part on said rotatable head, when rotated, contacting with the rear of said arm and depressing it, in which latter position said rotatable head and the coacting part thereon can clear said control element and be moved to a cleaning position at greater insertion within the space in the boiler, and a stop acting in conjunction with said arm to limit the angular rotation of said rotary head.

18. A soot-blower according to claim 6, wherein said means for opening and shutting the valve comprises a valve-cam located above the stem of the valve, having cam portions for opening and closing the valve, said valve-cam also having parts in position to be acted on by said part of the valve opening and shutting means which is connected to the carriage-moving means.

19. A soot-blower according to claim 6, wherein said means for opening and shutting the valve comprises a valve-cam having cam portions for opening and closing the valve, said valve-cam also having parts in position to be acted on by said part of the valve opening and shutting means which is connected to the carriage-moving-means, and said part of the means for opening and shutting the valve which is connected to said carriage-moving-means comprising a sprocket chain, and a pin on said chain which moves as the carriage moves, and which moves toward and from said valve-cam, and contacts therewith as the carriage closely approaches an inserted cleaning position of the cleaner element carried thereby.

20. A soot-blower according to claim 6, wherein said means for opening and shutting the valve comprises a valve-cam having a cam portion for opening and closing the valve, said valve-cam also having a finger in position to be acted on by said part of the valve opening and shutting means which is connected to the carriage-moving-means, and said part of the means for open-

ing and shutting the valve which is connected to said carriage-moving-means comprising a sprocket chain, and a pin on said chain, which moves as the carriage moves, and which moves toward and from said valve-cam and contacts with said finger as the carriage closely approaches an inserted cleaning position of the cleaner element carried thereby, and, during said approach, throws said valve-cam to valve opening position.

21. A soot-blower according to claim 6, wherein in said means for opening and shutting the valve comprises a valve-cam, having a cam portion for opening and closing the valve, said valve-cam also having a finger in position to be acted on by said part of the valve opening and shutting means which is connected to the carriage-moving-means, and said part of the means for opening and shutting the valve which is connected to said carriage-moving-means comprising a sprocket chain, and a pin on said chain, which moves toward and from said valve-cam and contacts with said finger as the carriage closely approaches an inserted cleaning position of the cleaner element carried by the carriage, and, during said approach, throws said valve-cam to valve opening position, said finger on said valve-cam being depressible to enable said pin on said sprocket chain to pass beyond it and to resume its position in the path of the pin on the said sprocket chain.

22. A soot-blower according to claim 6, wherein in said means for opening and shutting the valve comprises a valve-cam, having cam portions for opening and closing the valve, said valve-cam also having a finger by which it may be turned, and wherein said carriage-moving-means comprises a sprocket chain and two pins thereon constructed and arranged during the course of the movement of the sprocket chain to contact with said valve-cam-finger, one of said pins being arranged to contact with said valve-cam-finger and throw the valve-cam to valve opening position as the carriage closely approaches an inserted cleaning position of the cleaner element carried by the carriage, said valve-cam-finger being depressible by said pins to enable them to pass beyond said finger, said second pin making contact with said valve-cam-finger on the initial movement of said carriage-moving means in a direction to retract the carriage and the cleaner element carried thereby, and to throw said valve-cam-finger and the valve-cam to valve closing position.

23. A soot-blower of the retractable type comprising a cleaner element, a track, a carriage, movable on said track, a rotatable head on said carriage to which said cleaner element is attached, means for moving said carriage on said track to insert the cleaner element in and retract it from an operating position, means for rotating said rotatable head, a plurality of control elements for stopping and controlling the rotation of said rotary head at a plurality of inserted cleaning positions of said cleaner element, and means on said control element coacting with the part connected with said rotary head, at an inserted cleaning position of the cleaner element, to remove the stop interposed by said control element to further progress of said carriage and the parts carried thereby to another inward cleaning position.

24. A soot-blower according to claim 23, further including a valve for admitting and shutting off a supply of steam to said cleaner ele-

ment, and means for opening and shutting said valve through the intermediary of said carriage-moving-means, said carriage-moving-means comprising a part which coacts with said valve opening and shutting means, at a position of said carriage corresponding to its first inserted cleaning position, to open said valve, and having a part, at the last inserted cleaning position of said carriage, which coacts with said valve opening and shutting means to shut said valve on the initial retraction movement of said carriage moving means.

25. A soot blower according to claim 4, wherein in said valve is separated from the carriage and head.

26. A soot blower of the retractable type comprising a cleaner-element, a steam supply tube along which said cleaner-element reciprocates, a track, a carriage movable on said track, means attached to said carriage cooperating with said track to prevent said carriage being displaced vertically or laterally, means for moving said carriage on said track to insert the cleaner-element in and retract it from an operating position comprising a connection providing a limited lost motion between said carriage-moving-means and the carriage, a valve for admitting and shutting off a supply of steam to said cleaner-element, and means for opening said valve during the forward reciprocation of said cleaner-element and shutting said valve during the taking up of said lost-motion between said carriage moving means and said carriage, and prior to the rearward reciprocation of said cleaner-element comprising a part connected to said carriage-moving-means and a part in a position corresponding to an inserted cleaning position of said cleaner-element, said parts being constructed and arranged to open said valve through the intermediary of said carriage-moving-means at a position corresponding closely to an inserted cleaning position of said cleaner-element and to shut said valve through the intermediary of said carriage-moving-means while said carriage is at an inserted cleaning position of said cleaner-element and before said carriage-moving-means has completed the lost motion between it and said carriage and begins the retraction of said carriage and cleaner-element.

27. A soot blower of the retractable type comprising a cleaner element, means for moving said cleaner element to insert it in and retract it from an operating position, a valve for controlling the flow of steam to said cleaner element, and means actuated by said cleaner-element-moving-means for opening and closing said valve at an inserted position of said cleaner element, said cleaner-element-moving-means having a connection therein providing a limited amount of lost motion between the said moving means and the cleaner element on the actuation of said moving means in the retracting direction, said cleaner-element-moving-means comprising a part which acts on said means for opening and closing the valve to cause the latter to close the valve on the movement of said cleaner-element-moving-means in the retracting direction during the period of lost-motion between the cleaner element and said moving means, so that steam is cut off from said cleaner element before motion is taken up by the cleaner element in the direction of its retraction.

FREDERICK W. LINAKER.
